UNITED STATES PATENT OFFICE.

EDWARD GIOSEPH MARINETTI, OF RIVERSIDE, RHODE ISLAND.

WICK REMOVER.

Application filed May 11, 1926. Serial No. 108,440.

My present invention has to do with the wicks used in oil burning gas generators; and it has for its object to provide a simple and efficient device for quickly removing 5 the wicks of such generators and this without injury to the generator or the appurtenances thereof.

To the attainment of the foregoing, the invention consists in the improvement as 10 hereinafter described and definitely claimed.

In the accompanying drawings, forming part of this specification:—

Figure 1 is a sectional view illustrative of the manner in which a wick of an oil 15 burning gas generator is removed through the medium of my novel wick remover.

Figure 2 is an elevation of the wick remover per se.

Figure 3 is an enlarged fragmentary perspective of the upper portion of the tube of the wick remover.

Figure 4 is a diametrical section illustrative of a modified wick remover hereinafter explicitly referred to.

Similar numerals designate corresponding parts in Figures 1 to 3, to which reference 25 will first be made.

I show in Figure 1 a cylindrical gas generator 1, the said generator 1 being threaded 30 at one end as designated by 2 for the connection of an apertured cap 3 and being provided in spaced relation to the said cap with an interior straining diaphragm 4, of reticulated material. The generator characterized

35 as just described is conventional as is also the wick designated by 5 in Figure 1, and the purpose of my novel device is to remove the wick following the disintegration of carbon sediment designated by 6 in Figure 1 and which under ordinary conditions binds 40 the wick 5 in the generator casing 1 and renders the removal of the wick extremely difficult.

My novel wick remover is designated by 7, 45 and by comparison of Figures 1, 2 and 3, it will be noted that the wick remover is of tubular form, is equipped with a suitable handle 8 and is characterized by a forward flared end 9, toothed as designated by 10.

Manifestly the tubular device 7 may be 50 made of steel or any other material compatible with its purpose.

In the practical use of my improvement, the remover is inserted in the generator cas-

ing 1 so that a portion of the wick is received 55 in the remover, and the remover is then turned or reciprocated about its axis and at the same time is pressed into positive engagement with the collection of carbon so that the teeth 10 will gradually cut away the carbon 60 and in that way entirely free the wick from the generator casing wall, whereupon the wick may be readily removed in and by the tubular remover.

It will be apparent from the foregoing 65 that through the medium of my improvement not only is the wick removed, but the interior of the generator casing 1 is effectively cleared of carbon and other sediment as is desirable.

It will also be appreciated that my improvement is extremely simple and at the same time is so durable that it will last for an indefinite period of time.

The tubular wick 7* shown as a modification in Figure 4 differs from the tubular wick remover 7 of Figures 1 to 3 in that it has no flared upper end and in that it has no teeth 10. On the other hand, in the modified construction, the tube 7* is exteriorly 75 of even diameter to its end 10*, but interiorly the end portion of the tubular remover 7* is tapered to a sharp edge at the end 10* so that the modified embodiment is adapted to be used after the manner of a chisel for the 80 removal of the collected carbon before alluded to.

I have explicitly described the preferred embodiments of my invention in order to impart an exact understanding of the said 90 embodiments. I do not desire, however, to be understood as limiting myself to the precise structure disclosed, my invention being defined by my appended claims within the scope of which modifications may be made 95 without departure from my invention.

Having described my invention, what I claim and desire to secure by Letters-Patent, 100 is:—

1. A wick remover for the purpose described, tubular in form to receive a portion 105 of a wick and having a cutting forward end for the disintegration and displacement of carbon about a wick.

2. A wick remover for the purpose described, tubular in form to receive a portion 110 of a wick and having a cutting forward end for the disintegration and displacement of

carbon about a wick; the said tubular wick remover being equipped with a handle in spaced relation to its forward end, whereby it may be powerfully turned about its axis.

3. A tubular wick remover characterized by a flared and toothed forward end.

4. A tubular wick remover characterized

by a flared and toothed forward end; the said tubular remover being equipped in spaced relation with said forward end with a handle whereby it may be powerfully turned about its axis. 10

In testimony whereof I affix my signature.
EDWARD GIOSEPH MARINETTI.
